ATTORNEY

UNITED STATES PATENT OFFICE.

JOSEPH HERMAN, OF NEW YORK, N. Y., ASSIGNOR TO AMERICAN TELEPHONE AND TELEGRAPH COMPANY, A CORPORATION OF NEW YORK.

DIFFERENTIAL DUPLEX TELEGRAPH REPEATER.

Application filed June 26, 1926. Serial No. 118,692.

This invention relates to grounded direct current telegraph systems, and more particularly to the differential duplex repeater circuits employed in such systems.

5 The object of the invention is to provide improved arrangements for reducing interference with telegraph systems from alternating current power transmission systems.

10 It has been the practice heretofore to employ resonant shunts connected across the receiving relay windings of telegraph systems of the class to which the invention relates. These shunt circuits are tuned to the frequency of the interfering power currents, 15 offering a low impedance to these currents and a high impedance to the signaling currents.

15 In accordance with the invention described hereinafter, I provide an anti-resonant circuit in a novel arrangement, whereby a very high impedance is offered to power currents tending to flow into the repeater from the line.

20 The accompanying drawing shows in diagrammatic form a telegraph repeater circuit improved according to the invention. The telegraph repeater circuit consists of the telegraph line, the balancing artificial line, the sending relay and the source of direct current associated therewith, and the receiving relay having one winding in the line and one winding in the artificial line. The circuit connections of the above are old and well understood in the art.

25 My anti-resonant circuit consists of a transformer having a winding W_1 connected in series with the line and a winding W_2 connected in series with the artificial line, and of the condenser C connected in shunt between the line and the artificial line. This circuit is tuned to the frequency of the interfering power current and offers a very high impedance to such currents flowing from the line.

30 I connect the windings W_1 and W_2 of the transformer differentially with respect to signals sent to the line by the sending relay of the repeater. Accordingly, these windings have no effect on the signals from the

sending relay. This arrangement permits 50 of greater discrimination against the interfering current at the other end of the circuit.

It will be understood that whereas it has been necessary heretofore to employ separate anti-resonant circuits in the line and in the 55 artificial line of each repeater circuit, which arrangement affects both the transmitted and the received telegraph signals, I use the single and simple anti-resonant circuit arrangement disclosed above, and connect the 60 windings of the transformer as shown, thereby not only providing a very high impedance to the interfering currents tending to flow into the repeater, but also permitting 65 of greater discrimination at the other end of the telegraph system against the interfering power currents.

What is claimed is:

1. In a differential duplex telegraph repeater system, a sending relay, a receiving 70 relay, a line and an artificial line, a transformer having a first winding in series with said line and a second winding in series with said artificial line, said windings being connected differentially with respect to signals 75 sent to the line by said sending relay, and a condenser in shunt with the windings of said transformer to form a tuned circuit anti-resonant at the frequencies of interfering alternating currents. 80

2. In a differential duplex telegraph repeater system, a sending relay, a receiving relay, a line and an artificial line, a transformer having a first winding in series with said line and a second winding in series with 85 said artificial line, and a condenser in shunt with said windings, said windings being connected differentially with respect to signals sent to the line by said sending relay, and the inductance of said windings and the 90 capacity of said condenser being such that a high impedance is offered to interfering alternating currents flowing in the line.

In testimony whereof, I have signed my name to this specification this 24th day of 95 June, 1926.

JOSEPH HERMAN.
